DESIGN FOR A ROSARY OF THE STATIONS OF THE CROSS

John C. Kelley, New Haven, Conn.

Application February 1, 1944, Serial No. 112,404

Term of patent 3½ years

(Cl. D45—16)

To all whom it may concern:

Be it known that I, John C. Kelley, a citizen of the United States, residing in New Haven, county of New Haven, and State of Connecticut, have invented a new, original, and ornamental Design for a Rosary of the Stations of the Cross, of which the following is a specification, reference being had to the accompanying drawing forming a part thereof.

The figure is a plan view of a rosary of the stations of the cross, showing my design.

I claim:

The ornamental design for a rosary of the stations of the cross, as shown.

JOHN C. KELLEY.
